UNITED STATES PATENT OFFICE.

CHARLES GOETZ, OF WHEELING, WEST VIRGINIA, ASSIGNOR TO THE OHIO VALLEY CHINA COMPANY, OF SAME PLACE.

DESIGN FOR A COVERED DISH.

SPECIFICATION forming part of Design No. 24,512, dated July 30, 1895.

Application filed June 22, 1895. Serial No. 553,737. Term of patent 7 years.

To all whom it may concern:

Be it known that I, CHARLES GOETZ, a subject of the Queen of Great Britain, residing at Wheeling, West Virginia, have invented 5 or produced a new and original Design for Covered Dishes, of which the following is a full, clear, and exact specification.

This invention has for its object to provide a novel, handsome, and ornamental covered 10 dish for table or any other use, which presents to the eye a characteristic and distinguishing appearance.

The leading feature of the design resides in a covered dish the body of which is composed of three ornamental main sections 15 disposed horizontally and each formed with curved lines, so that it is approximately ogee-shaped on its surface, ornamental scrollwork extending along the upper portion of and 20 dividing the intermediate or central main section from the upper main section and ornamental scrollwork extending along the bottom portion of the intermediate or central main section and dividing it from the lower 25 main section.

The invention is illustrated by the accompanying drawings, in which—

Figure 1 is a side elevation of my new design for a covered dish. Fig. 2 is a top plan 30 view of the same, and Fig. 3 is a detail vertical sectional view of a portion of the covered dish to more clearly illustrate the approximately ogee-shaped surfaces of the main sections.

35 In the accompanying drawings the numerals 1, 2, and 3 indicate the three ornamental main sections disposed horizontally and arranged in order of sequence. The upper main section 1 is formed with curved lines 4 and 5, so that such section is approximately 40 ogee-shaped on its surface or in cross-section,

as will be best seen by reference to Fig. 3. The intermediate or central section 2 comprises curved lines 6 and 7, of greater radius than the curved lines 4 and 5, so that the surface of this section 2 is also approximately 45 ogee-shaped. The lower section 3 comprises curved lines 8 and 9 of less radius than the curved lines 6 and 7, and the surface of this section is also approximately ogee-shaped. 50

The line dividing the upper section 1 from the intermediate or central section 2 is provided with ornamental scrollwork 10, and the line dividing the said section 2 from the lower section 3 is also provided with ornamental scrollwork 12. The end sub-sections 13 and 14 are suitably ornamented and from such sub-sections project suitable handles 15 and 16.

The body of the dish is somewhat oblong 60 in outline and its upper edge is of an undulatory contour, as clearly shown in Fig. 2.

The cover of the dish represented in the drawings may be of any desired pattern, but it should conform with the outline of the 65 dish-body and be provided with an elevated handle 17.

The design provides a handsome and ornamental dish which presents a distinguishing characteristic and striking appearance 70 to the eye.

What I claim is—

The design for a covered dish, substantially as shown and described.

In testimony whereof I have hereunto set 80 my hand in presence of two subscribing witnesses.

CHARLES GOETZ.
